HOMER CLYDE SNOOK, OF CYNWYD, PENNSYLVANIA.

RECTIFYING APPARATUS.

Specification of Letters Patent.

Patented Apr. 25, 1916.

1,180,329.

Original application filed December 26, 1908, Serial No. 469,355. Divided and this application filed December 4, 1914. Serial No. 875,410.

To all whom it may concern:

Be it known that I, HOMER CLYDE SNOOK, a citizen of the United States, residing at Cynwyd, county of Montgomery, and State of Pennsylvania, have invented certain new and useful Improvements in Rectifying Apparatus, of which the following is a specification.

My invention relates to a system and apparatus for converting polyphase current, and particularly high tension polyphase current, into uni-directional current.

My invention resides also in a high tension polyphase rectifying switch.

This application is a division from my prior application, Serial Number 469,355, filed December 26, 1908.

For an illustration of one of the forms my invention may take, reference is to be had to the accompanying drawings, in which:

Figure 1 is a diagrammatic view illustrating the apparatus and circuit arrangements of my system. Fig. 2 is a vertical sectional view, partly in elevation, of a high potential three phase rectifying switch mounted in operative relation with a motor, inverted rotary or other suitable device, and a high potential three phase transformer. Fig. 3 is an end elevational view, partly in section, of the high potential three phase rectifying switch shown in Fig. 2. Fig. 4 is a view graphically representing the rectified current waves and their effect in the X-ray tube.

Referring to Fig. 1, L and L¹ are the conductors of an electric supply circuit leading to the motor side M of a motor generator or inverted rotary R, whose generator side G delivers three phase alternating current to the three conductors 1, 2 and 3, a reversing or pole changing switch A being connected in the conductors 2 and 3 for reversing the direction of energy flow in the X-ray tube X if for any reason it be in the wrong direction. In each of the conductors 1, 2 and 3 is inserted an adjustable non-inductive resistance 4 for maintaining the resistances of the three transformer primary circuits equal.

And the three movable contacts for adjusting the resistances 4 are preferably mechanically connected together, so as to insert or remove equal amounts of resistance in each primary. The conductors 1, 2 and 3 lead to the primaries p¹, p² and p³, of the high potential step up transformer T, each being

adjustable as to its number of turns, the three movable contacts for this purpose being preferably mechanically connected together so that the number of turns in the primaries is varied equally. These primaries are here shown connected in Y arrangement, though it is to be understood that the delta connection may be employed. The high potential secondaries s¹, s² and s³ are here shown as Y connected, as the preferred connection, though the delta connection is within my invention. The three phase transformer T having these three primary and secondary windings is of the closed magnetic circuit type and has a minimum or practically no magnetic leakage for purposes hereinafter referred to. The neutral or common point of the three secondary windings, when Y connected, is connected by conductor 5 to earth or ground at 6. And for this reason the Y connection is preferred.

From each secondary winding s¹, s² and s³ a connection is made through conductors h¹, h² and h³ to pairs of conducting arcs of the rectifying switch E, a choke coil D intervening in such connection if desired, for the purpose of preventing any high frequency oscillations (the coils D being high frequency choke coils) from running back to the transformer windings where they might cause insulation punctures or break-downs.

From the opposed arcs of the rectifying switch E extend conductors i and i' leading respectively to the cathode k and anode j of the X-ray tube X. An ammeter F is connected in series with the tube X to measure the current consumed therein, such ammeter being, for example, of the type described in Letters Patent of the United States No. 768,957, heretofore granted to me.

Referring to Fig. 2, a bench or base H, of wood or other suitable material, serves to support the high potential rectifying switch E, the transformer T (contained in the metal transformer case I, containing oil) and the motor generator or inverted rotary R. As here represented, R is an inverted rotary receiving direct current and delivering three phase alternating current.

A wooden spindle or shaft J has metal shaft terminals m, m having bearings n, n supported by the end walls o, o of the wooden covering or casing which incloses the high potential polyphase rectifying switch E. One of the terminal shafts m is connected

- by an insulating coupling P with the shaft q of the inverted rotary R. Extending through and carried by the spindle J are six metallic rods or wires r, s, t, u, v, and w, each incased in rubber or other insulating covering and support x. The wooden spindle J insulates each of these six rotating cross connectors or rods from every other, and the insulating covering x, preferably of hard rubber, insulates each of the cross connectors to prevent premature or undesired sparking during operation. These six cross connectors or metallic rods are divided into three pairs, the cross connectors of each pair being disposed at right angles with each other, but the cross connectors of the second pair progress at an angle of 60 mechanical degrees with respect to the cross connectors of the first pair, and the cross connectors of the third pair progress at an angle of 60 mechanical degrees with the cross connectors of the second pair or at an angle of 60 mechanical degrees with the cross connectors of the first pair. Cooperating with the cross connectors r, s respectively are the opposed pairs of conducting arcs 7, 8 and 9, 10, the arcs 7 and 9 being electrically connected together and with the conductor h² led up through the insulating tube 19 from the terminal of one of the high potential secondaries of the transformer T. Through a similar insulating tube 20 is led up a conductor h³ from the terminal of another high potential secondary which connects to the neighboring conducting arcs 11 and 13 opposed to the conducting arcs 12 and 14, the cross connectors t and u coöperating with these opposed pairs of arcs. Similarly, through the insulating tube 21 extends a conductor h¹ communicating with the terminal of the third high potential secondary winding of the transformer T, the conductor h¹ being connected to the arcs 15 and 17 which are opposed to the conducting arms 16 and 18 respectively, the cross connectors v and w coöperating with these opposed pairs of arcs. The cross connectors do not touch the arcs in passing them, short air gaps intervening over which the current sparks. The conducting arcs 8, 14 and 16 are electrically connected together and to the conductor i' and, as seen in Fig. 1, to the anode j of the X-ray tube X. And the arcs 10, 12, and 18 are connected together and to the conductor i which connects with the cathode k of the tube X.
- Between the neighboring pairs of the lower conducting arcs, as viewed in Fig. 2, which may be styled the supply arcs, since they are connected to the supply side of the switch E, are disposed the insulating barriers 22 and 23, of mica, micanite, glass, or any suitable highly insulating material. And between the upper conducting arcs 8 and 10, which are on the distributing side

of the switch E and may, therefore, be styled distributing arcs, is disposed a similar insulating barrier 24; and between the distributing arcs 12 and 14 is a similar insulating barrier 25; and between the distributing arcs 16 and 18 is a similar insulating barrier 26. These insulating barriers are supported, spaced and held in place by suitable means comprising vertically extending rods 27 and 28, preferably of insulating

The conducting arcs 7 to 18 inclusive, are supported upon the tubes 29, 30, 31, 32, 33, and 34, of porcelain, or other insulating material, disposed upon the parallel rods 35. And these cross connectors and their coverings and the wooden spindle J are all mechanically balanced so that the center of gravity of the moving system is in the axis of the rotating spindle J.

The spindle J being preferably mechanically connected to the rotating member which generates the three phase alternating current, insures that the rotating cross connectors are in exact synchronism with the alternating current delivered from the alternating current side of the inverted rotary R. Or, if the alternating current generator be driven by any other means, the spindle J is nevertheless preferably mechanically connected to the rotating element of the alternating current generator.

The conducting arcs, as here shown, for a three phase system, have an angular extent of something preferably slightly less than 60 mechanical degrees, 60 mechanical degrees in the switch E corresponding with 120 electrical degrees. Thus, in the example illustrated, the rotating element of the generator G produces two complete electrical cycles for each revolution, this implying a four-pole machine. It follows, therefore, that since the cross connectors of the different pairs are 60 degrees in advance or in arrears of each other, it means that these cross connectors are disposed at an angle of 120 electrical degrees with respect to each other, the same being the interval in electrical degrees between the different phases of a symmetrical three phase current.

The operation is as follows: The operator brings the motor M of the inverted rotary into communication with a source of current and brings the inverted rotary or the alternating current generator up to speed, thus generating three phase current of desired frequency and rotating the cross connectors of the rectifying switch E in synchronism with that current. The transformer T then delivers high potential three phase current which is rectified by the switch E and supplied to the tube X. Thus, assuming the cross connectors r, s, t, u, v and w to be rotating in a clockwise direction, as viewed in Figs. 1 and 3 the cross

connector *w* is just beginning to admit current from secondary *s*¹ through arcs 17 and 18 to the one terminal *k* of the X-ray tube *X*. Its companion cross connector *v* is out of circuit as is also the cross connector *u* associated with the secondary *s*³. Cross connector *t* is just leaving arcs 11 and 12, having heretofore admitted current from the secondary *s*³ to the terminal *k* of the tube. 5 Cross connector *s* is out of circuit but its associate *r* is admitting current from secondary *s*² through arcs 7 and 8 to the other terminal *j* of the X-ray tube. As these cross connectors continue to rotate they keep passing both the positive and negative current waves of each phase through the tube *X* all in the same direction; and more than this, they correlate and superimpose the different half waves of the phases so that for certain periods of time a plurality of phases 10 coöperate with each other in impressing energy upon the tube *X* all in the same direction, whereby the tube is always traversed by energy, and the minimum potential 15 to which the tube is subjected is greater than the maximum potential delivered by any one of the secondaries alone. The energy is all passed through the tube *X* in the same direction, the energy of each half wave of each 20 phase being passed through the tube and all in the same direction exciting the tube to great intensity, there being no time when there is no energy passing through the tube. And the minimum energy at any instant is 25 sufficient to fully excite the tube.

As seen from Fig. 4, the switch *E* rectifies the current in each phase, so that we have the overlapping half waves *a*, *b*, *c*, *a'*, *b'*, and *c'*, *a*, *b*, and *c* representing the three different 40 phases. *a'*, *b'* and *c'* indicate the rectified or turned over negative (for example) half waves. And the length of the conducting arcs of the switch *E* being substantially 120 electrical degrees, and the angular relation 45 of the cross connectors with respect to the windings on the rotating member of the alternating current generator is so chosen and fixed, that each cross connector is active or in circuit for a time corresponding with the 50 distance *d*. There results then in the circuit of the tube *X* a fluctuating current of frequency triple the frequency of a half cycle of one phase supplied by the transformer *T*, this triple frequency current being represented by the curve *e* in the upper part of 55 Fig. 4. This curve is obtained by adding the ordinates of the curves below during such periods as the different phases are actively in circuit as controlled by the switch *E*. It will be noted, therefore, that the 60 minimum potential upon the terminals of the tube *X*, represented by the distance *f*, is greater than the potential of any one of the secondaries of the transformer *T*. This 65 potential *f* is dependent upon the maximum

potential of a phase multiplied by twice the sine of half the angle between the phases. This curve shows that the tube *X* is constantly subjected to a potential whose minimum is *f* and which is always greater than 70 the potential delivered by one phase of the transformer *T*, and this minimum potential *f* is sufficient to excite the tube *X* to a very high intensity. This potential varies as shown by the upper curve *e* so that the 75 energy through the tube *X* fluctuates, but at no time has it a potential less than the potential *f*.

By having practically no inductance in the circuits of the primaries of the transformer *T*, other than their own inductances, and by making the transformer *T* of a minimum or practically no magnetic leakage, and by mechanically connecting the shaft *J* to the rotating element of the device generating the alternating current, I secure a maximum efficiency of conversion, along with an excitation of the tube *X* to an intensity which has never heretofore been attained, the features enumerated contributing to this result, and especially to the result of preventing inverse discharge in the tube *X*, inverse discharge being energy flowing in the wrong direction through the tube *X*. 95

The conducting arcs of the switch *E* are made somewhat less than 120 electrical degrees in extent to take care of the case where the currents in the three phases do not maintain an interval of 120 electrical degrees between each other, and to take care of any other departures from the ideal conditions. 100

While I have here illustrated my invention as involving a three phase current, it is to be understood that my invention refers to 105 polyphase currents in general, such as quarter phase or two phase currents or currents of other phase relations and numbers. And while I have shown the conducting arcs of the switch *E* in alinement, it is to be understood that they may be disposed out of alinement and the cross connectors then suitably changed in their relations to the arcs. 110

It is to be understood also that the arcs may be otherwise disposed, in which case a 115 greater number of insulating barriers may be required. In the arrangement illustrated a minimum of five insulating barriers is required, and this with the alinement of the conducting arcs makes the size of the rectifying switch a minimum for any given potential. 120

What I claim is:

1. A high potential polyphase rectifying switch comprising a pair of supply arcs for 125 each phase, a pair of distributing arcs for each phase, a cross connector coöperating with each pair of supply and distributing arcs, the cross connectors coöperating with the supply arcs of one phase being dis- 130

posed at 180 electrical degrees with respect to each other, a shaft for producing relative rotation between said arcs and cross connectors, the pairs of supply and distributing arcs being disposed side by side longitudinally of said shaft, the angular relation between cross connectors for the different phases and the angular extent of said arcs being such that at all times opposed supply and distributing arcs of each of a plurality of different phases are simultaneously in communication with each other, the supply arcs for all phases being disposed in alinement with each other, and the distributing arcs all being disposed in alinement with each other.

2. A high potential polyphase rectifying switch comprising a pair of supply arcs for each phase, a pair of distributing arcs for each phase, a cross connector coöperating with each pair of supply and distributing arcs, the cross connectors coöperating with the supply arcs of one phase being disposed at 180 electrical degrees with respect to each other, a shaft for producing relative rotation between said arcs and cross connectors, the pairs of supply and distributing arcs being disposed side by side longitudinally of said shaft, the angular relation between cross connectors for the different phases and the angular extent of said arcs being such that at all times opposed supply and distributing arcs of each of a plurality of different phases are simultaneously in communication with each other, the supply arcs for all phases being disposed in alinement with each other, the distributing arcs all being disposed in alinement with each other, the distributing arcs opposed to one of each pair of supply arcs being connected in parallel with each other, and the remainder of the distributing arcs connected in parallel with each other.

3. A high potential polyphase rectifying switch comprising a pair of supply arcs connected together and to the terminal of a phase circuit, a distributing arc for each supply arc, the length of each arc in mechanical degrees being substantially half of the electrical degrees corresponding with the interval between phases, a cross connector for each pair of supply and distributing arcs and passing through one cycle for two electrical cycles, the cross connectors for a pair of supply arcs being disposed at 180 electrical degrees with respect to each other, the angular relation between cross connectors for the different phases and the angular extent of said arcs being such that at all times opposed supply and distributing arcs of each of a plurality of different phases are simultaneously in communication with each other, the distributing arcs opposed to one of each pair of supply arcs being connected in parallel with each other, and the

remaining distributing arcs connected in parallel with each other.

4. A high potential polyphase rectifying switch comprising a pair of supply arcs connected together and to the terminal of a phase circuit, a distributing arc for each supply arc, the length of each arc in mechanical degrees being substantially half of the electrical degrees corresponding with the interval between phases, a cross connector for each pair of supply and distributing arcs and passing through one cycle for two electrical cycles, the cross connectors for a pair of supply arcs being disposed at 180 electrical degrees with respect to each other, the angular relation between cross connectors for the different phases and the angular extent of said arcs being such that at all times opposed supply and distributing arcs of each of a plurality of different phases are simultaneously in communication with each other, the distributing arcs opposed to one of the arcs being connected in parallel with each other, the remaining distributing arcs connected in parallel with each other, said cross connectors and arcs being rotatable with respect to each other, said supply arcs disposed in alinement with each other and spaced longitudinally of the axis of rotation, and the distributing arcs disposed in alinement with each other and spaced longitudinally of the axis of rotation.

5. A high potential polyphase rectifying switch comprising pairs of opposed conducting arcs and coöperating cross connectors, a pair of supply arcs for each phase, a pair of distributing arcs for each phase, the supply arcs disposed in alinement with each other, the distributing arcs disposed in alinement with each other, the angular relation between cross connectors for the different phases and the angular extent of said arcs being such that at all times opposed supply and distributing arcs of each of a plurality of different phases are simultaneously in communication with each other, half of the distributing arcs connected to each other and to one terminal of the consumption circuit, the remainder of the distributing arcs connected together and to the remaining terminal of the consumption circuit, an insulating barrier between neighboring pairs of supply arcs, and insulating barriers between distributing arcs connected to different terminals of said consumption circuit, one of said barriers disposed between neighboring pairs of interconnected distributing arcs.

6. A high potential three-phase rectifying switch comprising three pairs of conducting arcs in alinement with each other, opposed distributing arcs, cross connectors coöperating with the supply and distributing arcs, the angular relation between cross connectors for the different phases and

the angular extent of said arcs being such that at all times opposed supply and distributing arcs of each of a plurality of different phases are simultaneously in communication with each other, an insulating barrier between the middle pair of supply arcs and the end pairs of supply arcs, an insulating barrier between each of the end distributing arcs and the neighboring pairs of inter-connected arcs, and an insulating barrier between said pairs of inter-connected distributing arcs.

7. A high potential polyphase rectifying switch comprising two pairs of opposed supply and distributing arcs for each phase, the supply arcs for each phase being connected together, a distributing arc of each pair of distributing arcs being connected with one conductor of a consumption circuit, and the remaining distributing arcs connected with another conductor of a consumption circuit, a relatively rotating cross connector coöperating with each pair of supply and distributing arcs, the cross connectors for each phase being disposed at right angles to each other, the cross connectors of the different phases being disposed at angles with respect to each other corresponding with the angle of phase difference, and the angular relation between cross connectors between the different phases and the angular extent of said arcs being such that at all times opposed supply and distributing arcs of each of a plurality of different phases are simultaneously in communication with each other.

8. A high potential polyphase rectifying switch comprising two pairs of opposed supply and distributing arcs for each phase, the supply arcs for each phase being connected together, a distributing arc of each pair of distributing arcs being connected with one conductor of a consumption circuit, and the remaining distributing arcs connected with another conductor of a consumption circuit, a relatively rotating cross connector coöperating with each pair of supply and distributing arcs, the cross connectors for each phase being disposed at right angles to each other, the cross connectors of the different phases being disposed at angles with respect to each other corresponding with the angle of phase difference, the angular relation between cross connectors for the different phases and the angular extent of said arcs being such that at all times opposed supply and distributing arcs of each of a plurality of different phases are simultaneously in communication with each other, and means supporting all the supply arcs in alinement with each other and all the distributing arcs in alinement with each other.

9. The combination with a source of polyphase current, of means for transforming said current to high potential polyphase current, a consumption circuit, and a polyphase

rectifying switch intervening between said transforming means and said consumption circuit comprising two pairs of supply and distributing arcs for each phase, a distributing arc of each phase connected to one conductor of said consumption circuit, the remaining distributing arcs connected to the other conductor of said consumption circuit, means connecting together the supply arcs of each phase, and cross connectors rotating with respect to said arcs and separated therefrom by air gaps, the angular relation between cross connectors for the different phases and the angular extent of said arcs being such that at all times opposed supply and distributing arcs of each of a plurality of different phases are simultaneously in communication with each other, whereby uninterrupted current is delivered to said consumption circuit.

10. A high potential three-phase rectifying switch comprising a pair of supply arcs for each phase, a pair of distributing arcs for each phase, a cross connector coöperating with each pair of supply and distributing arcs, the cross connectors coöperating with the supply arcs of one phase being disposed at 180 electrical degrees with respect to each other, means for producing relative rotation between said arcs and cross connectors, the angular extent of said arcs being substantially 120 electrical degrees, the angular length of said arcs and the angular relation of the cross connectors for the different phases being such that at all times opposed supply and distributing arcs of each of a plurality of different phases are simultaneously in communication with each other.

11. A high potential polyphase rectifying switch comprising a switching mechanism for each phase comprising stationary and movable conductors coöperating with that phase only to direct current always in the same direction through the consumption circuit, the movable elements of all said mechanisms moving in unison with each other and in synchronism with the current, at least two of said switching mechanisms being at all times and simultaneously in communication with the consumption circuit.

12. A high potential polyphase rectifying switch comprising a switching mechanism for each phase comprising stationary and movable conductors coöperating with that phase only through spark gaps to direct current always in the same direction through the consumption circuit, the movable elements of all said mechanisms moving in unison with each other and in synchronism with the current, at least two of the switching mechanisms of different phases being at all times in communication with the consumption circuit.

13. A high potential polyphase rectifying switch comprising a pair of switches for

each phase comprising relatively movable ares, and cross connectors coöperating through spark gaps to direct current always in the same direction to the consumption circuit, the movable elements of all said switches moving in unison with each other and in synchronism with the current, at least two of said switches of different pairs being at all times in communication with the consumption circuit, the companion

switches of said two switches being simultaneously out of communication with the consumption circuit.

In testimony whereof I have hereunto affixed my signature in the presence of the 15 two subscribing witnesses.
